UNITED STATES PATENT OFFICE.

HORACE P. STEWART, OF GRAND RAPIDS, MICHIGAN.

POISON-INDICATOR.

1,009,597.

Specification of Letters Patent. Patented Nov. 21, 1911.

Application filed August 15, 1911. Serial No. 644,119.

To all whom it may concern:

Be it known that I, HORACE P. STEWART, a citizen of the United States, residing at Grand Rapids, in the county of Kent and State of Michigan, have invented certain new and useful Improvements in Poison-Indicators, of which the following is a specification, reference being had therein to the accompanying drawing.

10 This invention relates to bottle stoppers and the principal object of the same is to provide the stopper with a plate which is embedded in the top of the stopper and is provided with a toothed edge so that the stopper will indicate that the bottle contains poison. This will prevent the bottle being opened in the dark and the contents taken as the plate will prick the fingers, and thus indicate that the bottle contains poison. This 15 plate is so mounted within the cork that it will not readily work loose, it being partly embedded so that it cannot be twisted out of position.

20 This invention is illustrated in the accompanying drawings, wherein—

Figure 1 is a section through a bottle having the indicating cork inserted therein, the cork being also shown in section. Fig. 2 is a sectional view taken through the cork at 25 right angles to the section shown in Fig. 1. Fig. 3 is a perspective view of the cork with the plate removed.

Referring to the accompanying drawings by numerals, it will be seen that the cork 10 is provided with a slot 11 formed in its outer end, and that a longitudinally extending socket 12 extends into the cork from the point adjacent the center of the groove 11. The plate 13 is semi-circular in shape and is

provided with teeth 14 along its outer edge 40 so that when a person attempts to remove the cork in the dark the fingers will engage the teeth and thus notify the person that the bottle contains poison. The plate is seated within the groove 11 and has a prong 15 ex- 45 tending into the socket 12 and secured there- in by any suitable means, such for instance as cement or glue.

It should be noted that the prong 15 and socket 12 are rectangular in cross section so 50 that the prong cannot be turned in the socket. It should also be noted that by hav- 55 ing the plate seated within the groove 11 that the plate is prevented from turning thus holding the plate rigidly in position. It will also be obvious that if the cork be- 60 comes stuck in the bottle, that the plate may be used to twist the cork loose and due to the fact that it is seated within the groove 11 will not twist loose but will act as a very 65 efficient means for loosening the cork.

What I claim is:—

A cork provided with a transversely ex- 65 tending groove formed in its outer end and with a longitudinally extending socket lead- 70 ing into said cork from said groove, an indicating plate seated within said groove, and a prong extending from said plate into said socket whereby said plate will be held rigidly 75 within said groove, said groove preventing rotation of said plate.

In testimony whereof I hereunto affix my signature in presence of two witnesses.

HORACE P. STEWART.
